UNITED STATES PATENT OFFICE.

WILLIAM K. HENRY, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR-STOP MECHANISM.

1,056,990.

Specification of Letters Patent. Patented Mar. 25, 1913.

Application filed November 14, 1912. Serial No. 731,293.

To all whom it may concern:

Be it known that I, WILLIAM K. HENRY, a citizen of the United States, residing at New Britain, Hartford county, State of Connecticut, have invented certain new and useful Improvements in Door-Stop Mechanism, of which the following is a full, clear, and exact description.

This invention relates to a door stop mechanism used in conjunction with door closers, and relates more particularly to an improved construction which adapts the device for use in connection with doors such as those of coupon rooms, telephone booths, etc., where- 10 in it is desirable to cause the door to remain partially open when the room or booth is not in use, and yet such that whenever the door or booth is in use, the occupant may readily close the door. It is the custom in 15 such cases to leave the door partially open to indicate that the compartment to which it furnishes access is not occupied; hence the advantage of providing means for holding the door partially opened.

20 My present invention provides an improved form of stop mechanism of this character wherein it is possible to vary the degree to which the door is held open, and wherein the device is adapted for use on both right and left hand doors. In addition, the structure of the stop mechanism permits the door to be closed by the user of its compartment even when held open by the stop mechanism in its normal operation. 25 These and other advantages are described in detail in the following specification, taken in connection with the accompanying drawings, forming part thereof and illustrating a preferable embodiment of the invention.

30 In these drawings: Figure 1 is a top plan view of a door and casing showing my improved form of stop mechanism applied to the door closing mechanism thereof, the door being shown in opened position. Fig. 2 is a view in front elevation of the parts shown in Fig. 1. Fig. 3 is a fragmentary view in elevation of the chamber of the closer mechanism showing the checking mechanism applied thereto and in checking position. Fig. 4 is a similar view showing the checking parts in a different position. Fig. 5 is a top plan view of the cylinder of the closer

mechanism, the lever arm being removed therefrom. Fig. 6 is a partial bottom plan view of the lever arm of the closer mechanism.

55 Referring to the drawings by numerals, 1 indicates a door casing and 2 a door hinged thereto.

3 designates a lever arm controlled by a suitable door closer mechanism, the particular specific construction of which is immaterial, and 4 a link pivotally connected at one end to the lever arm 3, and at its other to a bracket 5 suitably secured to the door 65 casing 1.

The closer mechanism referred to is contained, in the present instance, in a chamber 6 which is provided with a suitable bracket 7 adapted to be secured to the door 70 2, the end of the lever arm 3 being operatively connected to this closer mechanism. The tendency of this closer mechanism is to move this lever arm to move the door to closed position, as is well understood in the 75 art.

8 designates a part of the closer mechanism carried by the chamber 6, and 9 a cooperating dog carried by the lever arm 3. The upper face of the lever arm 3 adjacent 80 the point to which its end is connected to the closer mechanism, is provided with a recess 10 within which is seated a leaf spring 11, one end of said spring being secured to the arm 3 and the other end free 85 being provided with a stud 12 extending transversely therefrom and through an aperture 13 formed in the lever arm 3 at that point, said stud being freely movable in said aperture and being normally depressed by its leaf spring 11. The lower end of this stud, when so depressed, extends below the under face of the lever arm 3 and has pivotally secured thereto a pawl 14 having its lower end 15 beveled to a point so 90 as to form substantially a right angle.

From the upper edge of the cylinder of the chamber 5 is detachably secured a split ring member or collar 16 which may be rigidly secured to said chamber at any desired position thereon by means of a clamping screw 17 cooperating with its split ends. Extending radially from the edge of this ring is an offset 18 lying in the arc of swing of the

pawl 14 carried by the lever arm 3. This offset 18 is provided with a recess 19 extending inwardly from its outer edge, the walls of this recess being preferably straight and at right angles to its base and forming opposite stop shoulders or abutments 20 and 21 which make it possible to use the stop mechanism with either right or left hand doors, as will be more clearly seen later.

10 It will be obvious that the closer chamber 5 and its abutment carrying collar are stationary relatively to the pivoted lever arm 3 which moves relatively thereto upon the opening and closing of the door. It will be 15 obvious also that the pawl 14 will be aligned with and contact with the offset 18 of the collar 16 at a certain period during the relative movement between the lever arm 3 and the chamber 6 of the closer mechanism.

20 The collar 16 is positioned to bring its offset portion to any point desired, which point determines the degree to which the door is held open, the stop mechanism operating as follows: Upon the opening movement of the door, the pawl 14 will ride freely over the offset 18 should the door be opened beyond that point, and in the normal operation of the door when it is not desired to hold it open, the door will close freely the 25 pawl 14 riding freely over the offset 18 from the opposite side. When, however, it is desired to hold the door opened, the door is moved to bring the end of the pawl member in the recess 19 of the offset 18. The 30 tendency of the closer mechanism will then move the lever arm 3 to bring one beveled edge of the pawl 14 against one of the stop shoulders or abutments, as 20 in Fig. 3 of the drawings, the other beveled edge resting 35 upon the base of the recess. In this position the stop shoulder 20, aided by the spring 11, offers a sufficient resistance to prevent a further closing of the door under the influence of the closer mechanism alone.

40 If extra pressure is applied to the door 2 in a direction to close the same, as by the occupant of a compartment pulling the door inwardly, the beveled end of the pawl 14 pressing against the stop shoulder 20 will move the stud 12 upwardly against the pressure of the leaf spring 11, raising said spring (see Fig. 4) so that the beveled end of the pawl is moved out of contact therewith, the closer mechanism now acting to 45 move the door to closed position. It will be seen from the foregoing that by varying the position of the offset 18 on the chamber 6 of the closer mechanism, the point at which the door is held opened may be varied at will. The opposite stop shoulder 21 is provided in order that the stop mechanism may be used with doors oppositely hinged to those whose operation causes the beveled end of the pawl member to engage 50 the stop shoulder 20; in other words, it en-

ables the stop mechanism to be applied without structural change, to both right and left hand doors. The operation of the shoulder or abutment-engaging pawl member is similar in each case.

While I have described and illustrated herein a specific embodiment of my device, I desire it understood that various structural changes are possible within the spirit of the invention and the scope of the appended claims.

What I claim, therefore, and desire to secure by Letters Patent is:

1. In a door stop mechanism, a stationary part provided with a portion grooved to form two opposite abutment shoulders, a pivoted part movable relative to said stationary part and its abutment shoulders, an abutment engaging member pivotally carried by said relatively movable pivoted part and riding freely over said abutment shoulders but adapted to be engaged with opposite shoulders to prevent relative movement of said pivoted part in opposed directions, and a yielding support for one of said cooperating abutment parts.

2. In a door stop mechanism, a stationary part, a member detachably and adjustably secured thereon and having an offset portion grooved to form two opposite abutment shoulders, a pivoted part movable relative to said stationary part and its abutment shoulders, an abutment engaging member pivotally carried by said relatively movable pivoted part and riding freely over said abutment shoulders but adapted to be engaged with opposite shoulders to prevent relative movement of said pivoted part in opposed directions, and a yielding pivot mounting for said abutment engaging member.

3. In a door stop mechanism, a stationary part, a member detachably and adjustably secured thereon and provided with a laterally offset portion having a groove therein forming therewith opposite and complementary abutment shoulders, a pivoted part movable relative to said stationary part and said abutment shoulders, a leaf spring carried by said pivoted part having a stud projecting from its free end, an abutment engaging member pivotally carried by said stud and riding freely over said abutment shoulders but adapted to engage with opposite abutment shoulders to prevent movement of said pivoted part in opposed directions.

4. In a door stop mechanism, a stationary part provided with a portion grooved to provide a base and two opposite abutment shoulders at right angles to said base, a pivoted part movable relative to said stationary part and its abutment shoulders, a dog pivotally carried by said relatively movable pivoted part, having a V-shaped free end provid-

ing beveled edges substantially at right angles to each other, said dog riding freely over said abutment shoulders, but being adapted to engage its free end with said base and an abutment shoulder in opposite directions of movement of said pivoted part to prevent relative movement of said part in such op-

posed directions, and a yielding support for one of said coöperating abutment parts.
